DESIGN.

J. E. MILLER.

GLASSWARE.

No. 16,997.

Patented Nov. 23, 1886.

UNITED STATES PATENT OFFICE.

JOHN E. MILLER, OF PITTSBURG, PENNSYLVANIA.

DESIGN FOR GLASSWARE.

SPECIFICATION forming part of Design No. 16,997, dated November 23, 1886.

Application filed February 18, 1886. Serial No. 192,457. Term of patent 7 years.

To all whom it may concern:

Be it known that I, JOHN E. MILLER, of Pittsburgh, in the county of Allegheny and State of Pennsylvania, have invented and produced a new and useful Design for Glass Vessels; and I do hereby declare the following to be a full, clear, and exact description thereof.

The accompanying drawing, forming part of this specification, illustrates a glass vessel in which my design exists.

The sides of the vessel are provided with a series of grooved or sunken lines, *a*, and a second series of transverse grooved or sunken lines, *b*. At the intersection of these lines there is a central rosette or diamond, *c*, and diagonally-projecting prismatical spikelets *d*, which imparts to the intermediate checker-squares, *e*, the configuration of Maltese crosses.

I have shown the superficial pattern above described intersected by a series of vertical prismatic stripes, *f*, and the upper rim of the vessel scalloped and indented, as at *i*, the apices of the scallops coinciding with the stripes *f*. The latter stripes are connected by bands *h*, which extend adjacently to the vessel's rim and bound the cross pattern.

The leading features of the design are indicated in the following claims.

I claim—

1. The design for glass vessels herein shown and described, the same consisting in the intersecting lines *a b*, projected at right angles to each other on the sides of the vessel, and the diagonal prismatical spikelets *d*, extending from the angles of intersection of the lines *a b*, substantially as shown and described. 30

2. The design for glass vessels herein shown and described, the same consisting of the flaring curved surface of the leaves or sections divided by the lines *f*, the said surfaces being ornamented with diagonal spikelets extending from angles of intersecting lines *a b*, as set forth. 40

3. The design for glass vessels herein shown and described, the same consisting of the flaring curved surface of the leaves or sections having curved rims forming scallops, substantially as shown and described. 45

In testimony whereof I have hereunto set my hand this 4th day of February, A. D. 1886.

JOHN E. MILLER.
